GROUND CLAMP

Cecil C. Rinehuls, Largo, Fla. (R.D. 1, Box 76, Lake Millsite, Bartow, Fla.), and Paul O. C. Jackson, 10720 59th Way N., Largo 2, Fla.

Filed Jan. 22, 1960, Ser. No. 4,112

1 Claim. (Cl. 339—13)

This invention relates to ground clamps and more particularly to a ground clamp capable of being used with various sizes of conduit or electrical metal tubing, cable or other commonly used electrical conductors.

An object of the invention is to provide a mechanically simple and practical ground clamp which will serve its intended purpose very effectively. Often, ground connections are concealed in buildings, even though this is poor practice. Then, if a faulty ground condition occurs, there is considerable difficulty in first finding the location of the ground connection and second, obtaining access to it. Furthermore, sources of electrical difficulties indicate checking the ground clamp, even though the ground connection is not faulty. When the ground connection is not readily accessible, the same difficulties are encountered.

In those cases where the ground connection is actually faulty, there appears to be little or no excuse for this because faulty grounds often occur after long periods of satisfaction.

An object of this invention is to provide an easily applied ground clamp which will assure an excellent ground for an electrical system not only at original installation but for an indefinite period.

An important feature of the invention is found in the adaptability of the clamp to receive more than one commonly used size of conduit, E.M.T., BX, etc.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a perspective view showing the ground clamp in use;

FIGURE 2 is a sectional view taken on the line 2—2 of FIGURE 1; and

FIGURE 3 is an elevational view of the ground clamp shown in FIGURE 1.

In the accompanying drawings there is an illustration of a pipe 12 which is assumed to be grounded and to which the wire 14 must be connected for electrical continuity. The wire 14 could very easily be substituted by stranded wire, this being immaterial insofar as the principles of the invention are concerned.

Ground clamp 16 is made of a first clamp section 18 and a second clamp section 20 and the sections are mechanically coupled together, for instance, by screw 22 which serves a dual purpose. The first function of the screw 22 is to connect the sections 18 and 20, and the second function, when applicable, is to function as a set-screw by having the extremity thereof engage pipe 12 as shown in FIGURE 2.

Clamp section 18 has two parts 24 and 26, each of which has a pair of ears 27, 28 and 29, 30 protruding

2

laterally outwardly from recessed intermediate parts 32 and 34, respectively. Screws 38 and 40 are passed through openings in ears 27, 28 and are screwed into tapped openings in ears 29, 30 so that upon tightening screws 38 and 40, the two parts 24 and 26 of clamp section 18 are brought tightly to bear against the outer surface of pipe 12. Screw 22 is engaged on a tapped opening in the intermediate part 34 of section 18, and it is passed through an opening in plate 46 which extends laterally outwardly from the body 48 of section 20 and which constitutes a part of section 20.

Body 48 has a larger diameter cylindrical wall 50 and a smaller diameter cylindrical wall 52, and the walls are integrally joined. Shoulder 54, which is circular, is at the juncture of walls 50 and 52 and forms an abutment or stop against which conduit 56, electrical metallic tubing, BX, etc. abuts. The cylindrical wall 52 is adapted to receive a smaller diameter conduit 56 or the like. Consequently, there is a shoulder 60, formed by a circular flange, within cylindrical wall 52. The shoulder 60 is located between the two ends of the wall 52.

There is means for engaging the conduit 56 or the like, regardless of whether it is positioned within the wall 52 or cylindrical wall 50. The preferred means consists of a pair of setscrews 64 and 66 located in threaded openings in the walls 50 and 52. The setscrews are adapted to firmly engage the outer surface of the side wall of the conduit 56.

Wire 14 is carried by conduit 56, and it extends beyond the end thereof so that a portion of the wire is located between pressure foot 68 and the lower surface of wall 52. The pressure foot is swivelly connected to screw 70, and the screw is passed through a tapped opening in cylindrical wall 52. Screws 70, 66 and 64 have screwdriver slots therein to facilitate turning of the screws, in other words, the screws are conventional.

In the use of ground connector 20, it is immediately evident that the ground connector is a threadless ground connector in a sense that the threading of the rigid conduit 56 is eliminated. When E.M.T. is in the building or at least, used for housing the ground wire, an E.M.T. connector is eliminated. The ground wire is not exposed as it is secured inside the grounding clamp, and this prevents damage to the ground wire. The installation of ground clamp 20 is certainly considerably easier for the electrician since all that he has to do is insert the wire into the clamp and tighten the grounding screw and E.M.T. screw.

The foregoing is considered as illustrative only of the principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention as claimed.

What is claimed as new is as follows:

A grounding coupling for an electric conductor of the type including a wire enclosed in a conduit, said coupling comprising a conductive sleeve mounted on an end portion of the conduit in communication therewith and projecting longitudinally therefrom, means for securing the sleeve on the conduit, means for clamping the wire in

the projecting end portion of the sleeve in contact therewith, and means for electrically connecting the sleeve to a grounding pipe, the last named means comprising a conductive clamp including a pair of opposed jaws for receiving and gripping the pipe therebetween, and a screw rotatably mounted on the sleeve and threaded through one of the jaws and engageable with the pipe for mounting the clamp on the sleeve and for frictionally securing said clamp against slippage on the pipe, the second named means including a screw threadedly mounted in 10 the sleeve, and a pressure foot swivelly mounted on the second named screw and engageable with the wire for clamping same against the sleeve.
